[57] CLAIM

The ornamental design for a cap with size adjustment mechanism, as shown and described.

DESCRIPTION

FIG. 1 is a perspective view of the adjustable cap with size adjustment mechanism showing my new design as viewed from above the rearward end of the right-hand side of the cap;

FIG. 2 is a perspective view thereof, as viewed from below the rearward end of the left-hand side of the cap;

FIG. 3 is a perspective view thereof, as viewed from below the forward end of the right-hand side of the cap;

FIG. 4 is a perspective view of the cap with size adjustment mechanism illustrated in FIG. 3, the brim is broken way for purposes of illustration;

FIG. 5 is a fragmentary perspective view of a back portion of the cap illustrated in FIG. 1, wherein an alternate size adjustment mechanism of the cap is shown;

FIG. 6 is a fragmentary perspective view of a back portion of the cap illustrated in FIG. 1, wherein a second alternate size adjustment mechanism of the cap is shown;

FIG. 7 is a fragmentary perspective view of the back portion of the cap illustrated in FIG. 5, as viewed from below the forward end of the right-hand side of the cap;

FIG. 8 is a fragmentary perspective view of the back portion of the cap illustrated in FIG. 6, as viewed from below the forward end of the right-hand side of the cap; and,

FIG. 9 is a perspective view of a third alternate design, similar to the design illustrated in FIG. 1-4, wherein the cap is illustrated without stitching and vent holes. In each embodiment of the cap the right-hand side of the cap in the above-referenced designs is substantially the same as the left-hand side of the cap. Additionally, the dashed lines in FIG. 1 through 8 represent conventional stitching.
